US00D901447S

(12) **United States Design Patent** (10) Patent No.: **US D901,447 S**
deBock et al. (45) Date of Patent: **** Nov. 10, 2020**

(54) **REMOTE**

(71) Applicant: **SPR Therapeutics, Inc.**, Cleveland, OH (US)

(72) Inventors: **Matthew G. deBock**, Morrisville, NC (US); **Joseph W. Boggs, II**, Chapel Hill, NC (US); **Matthew J. Wunzin**, Cleveland, OH (US); **Robert B. Strother, Jr.**, Willoughby Hills, OH (US); **Devin Sell**, Brecksville, OH (US); **Mark R. Stultz**, Maple Grove, MN (US); **Bradley A. Lewis**, Lyndhurst, OH (US)

(73) Assignee: **SPR Therapeutics, Inc.**, Cleveland, OH (US)

(**) Term: **15 Years**

(21) Appl. No.: **29/651,468**

(22) Filed: **Aug. 16, 2018**

(51) LOC (12) Cl. **14-03**

(52) U.S. Cl.

USPC **D14/218**

(57) **CLAIM**

The ornamental design for a remote, as shown and described.

DESCRIPTION

FIG. 1 is a top perspective view of a remote showing our new design;

FIG. 2 is a top perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the figures show portions of the remote that form no part of the claimed design.

1 Claim, 7 Drawing Sheets
